CYLINDER LOCK

Roger H. Ducey, Belmont, Mass.

Application August 3, 1945, Serial No. 608,659

1 Claim. (Cl. 70—99)

1

This invention relates to improvements in locks and the object of the invention is to provide a cylinder type lock of simple and inexpensive construction of greater safety than has heretofore been produced.

Usual locks are provided with a spring which holds the bolt or latch of the lock in position to be engaged by a key or in case of cylinder locks with a cam or other actuating device secured to the rotatable barrel of the cylinder which, when the key is inserted and the barrel rotated, will cause the bolt or latch to be moved to or from locking position according to the character of the lock. Such springs are likely to break or to become ineffective after long use.

One of the objects of the invention is to provide a lock which will not require use of a spring of this character and in which means integral with the barrel of the cylinder lock is adapted to be moved upon rotation of the barrel directly into interengagement with the complementary locking member upon a relatively movable member adapted to be united thereto.

Usual locks are so constructed as to enable the key to be removed when the barrel of the cylinder is either in locked position or in unlocked position.

One of the objects of the invention is to provide means for preventing the key from being removed from the lock when the barrel of the lock is rotated to unlocking position.

A further object of the invention is to provide a construction in which the invention may be embodied in various forms of locks such, for example, as those which lock together two relatively sliding members, or members one of which swings relatively to a stationary member, in other words, to provide a lock of universal adaptation.

These and other objects and features of the invention will more fully appear from the following description and the accompanying drawing and will be particularly pointed out in the claim.

Preferred embodiments of the invention are illustrated in the accompanying drawing, in which,

Fig. 1 is a view partially in horizontal section for uniting two relatively sliding members, such as sliding doors, or for locking the sliding door to a stationary door frame;

Fig. 2 is a side elevation of the same;

Fig. 3 is a view mainly in horizontal section illustrating a pivotal latch type which is adapted to be applied either to relatively sliding members or to members one of which is hinged;

Fig. 4 is a view of the construction illustrated

2

in Fig. 3 showing one of the members in section and illustrating in full lines the latch in locking position and in dotted lines the latch in released position;

Fig. 5 is a view partially in vertical section of a padlock embodying the invention in which the hasp member is in unlocked position;

Fig. 6 is a detail view partially in vertical section illustrating the construction shown in Fig. 5 with the hasp in locked position;

Fig. 7 is a transverse sectional view on line 7—7 Fig. 5, viewed upwardly;

Fig. 8 is a detail sectional view on line 8—8 Fig. 6;

Fig. 9 is a perspective view of the cylinder lock and a portion of the complementary locking member, viewed from the rear end of the cylinder lock, and illustrating complementary parallel slots in the barrel of the lock adapted to enter the recesses in the complementary locking member;

Fig. 10 is a view of a cap adapted to be applied to the head of the cylinder lock to prevent entrance of water into the keyhole of the lock; and

Fig. 11 is a detail view of the body of the lock illustrating the rotatable barrel of the lock, the complementary pins which are actuated by the key in locked position, and showing in dotted position the construction which will prevent removal of the key when the barrel is rotated to lock-releasing position.

The construction illustrated in Figs. 1 and 2 shows the embodiment of the invention in a construction in which the members to be locked

are adapted to be moved relatively end to end or edge to edge as, for example, sliding doors or a sliding door movable into engagement with a door frame. In this construction one of the members, such as a door or door frame 1, has fixedly secured to its edge an angle plate one member or flange 2 of which is secured by screws 3 to the edge of one of the doors or to the door jamb.

The other member or flange 4 of the angle plate is provided with a cylindrical aperture 5 at a distance from its edge and a relatively narrow slot 6 leads from said edge to the cylindrical aperture.

The complementary locking member, which is mounted in the other relatively movable member 7 such as a door, comprises a generally cylindrical body or casing 8 opposite sides of which are slabbed off to provide parallel walls 9 and 10 adapted to fit within a socket 11 in the member 7 and which when inserted in the member 7 will prevent rotation of the body by reason of the engagement of the walls 9 and 10 with the par-

55

allel walls of the socket. The body 8 is provided with an enlarged integral flange 12 adapted to be countersunk into the member 7 with the outer face thereof flush with the outer face of the member 7. The flange 12 is provided with an integral boss 13 which is engaged by a screw 14 the head 15 of which is countersunk into the member 7.

The lock, which is of the cylindrical tumbler lock type, comprises a cylindrical barrel 16 which is rotatably mounted in the body 8 and extends beyond the flanged end 12 of the casing, and is provided with an enlarged head 17 which desirably has an outwardly conical edge 18. The barrel 16 is provided intermediate of the flange 12 of the body and the head 17 of the cylinder with parallel slots or grooves 19 which are parallel with the walls of the keyhole 20 adapted slidably to fit within the groove 6 in the flange 4 of the complementary locking member. When the door members 1 and 7 are moved to abutting position the slots 19 will permit the barrel to be moved through the slot 6 in the flange 4 of the complementary member into registry with the slot 6 in the flange 4 of the complementary member and then rotated a quarter turn to a position in which the grooves 19 are at right angles to the slot 6, thereby preventing withdrawal of the barrel of the lock through the slot 6 as illustrated in Fig. 2.

One of the objects of the invention as above stated is to provide means for preventing removal of the key from the lock unless the barrel is rotated to locking position. In the construction shown in Figs. 1 and 2 the key can be withdrawn from the lock only when the parallel grooves 19 are at right angles to the slot 6, or when the relatively movable members have been separated sufficiently to withdraw the barrel of the lock through the slot 6 and the barrel again rotated to locking position at right angles to the position in which the barrel enters the slot 6.

The construction of the lock to accomplish this purpose is similar to that of an ordinary cylinder lock with the exception that the complementary pins or tumblers which are operated by the insertion of the key to permit rotation of the barrel are so constructed that when the barrel is rotated the pins, which are in the barrel, are so held in engagement with the notches of the key as to prevent withdrawal of the key.

In usual cylinder lock constructions the barrel 16 of the lock is provided with one or preferably several cylindrical tumblers or pins 21 having rounded or conoidal tips adapted to be engaged by the key when it is inserted in the lock and a like series of pins or tumblers 22, which are mounted in the body of the lock in alignment with the pins in the lock. The pins 22 are each backed by a spring 23 which normally forces them and the pins into conical sockets in the keyway of the lock, some or all of the pins 22 then extending into the barrel of the lock. Upon insertion of the key the pins 21 are forced longitudinally radially of the cylinder to raise the pins 22 over the crests between the notches of the key and then the respective pins 21 are forced downwardly into the barrel until the contact ends of the pins 21 and 22 are in the circumferential line of the cylinder, whereupon the barrel can be rotated.

In the present construction one or more of the cylinder pins are of such length that when the barrel is rotated by the key the outer ends of the barrel pins so nearly engage the surrounding

cylindrical surface of the body that the key cannot be withdrawn. This construction is common to all the species of locks illustrated in the accompanying drawing.

The construction shown in Figs. 3 and 4 comprises a locking device which is adapted either to relatively sliding door members or to a swinging door. In this construction the stationary member 24, such as a door frame or jamb, is provided with a recess or socket 25 having secured over it a plate 26 having a slot 27 which terminates short of the bottom of the recess or socket providing a ledge 28 adapted to be engaged by a latch. The barrel 16 of the lock has fixedly secured to its inner end a latch 29 having a hook-shaped end 30 adapted to engage the ledge 28 of the plate 26, so that the latch is to all intents and purposes integral with the barrel of the lock. In this construction as in that previously described the key can only be inserted when the latch is positioned for locking engagement with the ledge 28 and the key can only be removed when the relatively movable members are locked together.

In order to enable the assembled lock to be inserted in a door the edge of the door may be provided with a suitable slot 31 preferably at a suitable angle to the horizontal through which the latch 29 may be inserted laterally and a suitable recessed plate 32 thereafter countersunk in the edge of the door to overlie the slot 31.

The construction shown in Figs. 5-8 show the invention as applied to a padlock. In this construction the padlock comprises a solid body 33 and as illustrated is of transverse elliptical cross section but of course may be of any desired shape and is provided with a longitudinal generally cylindrical bore having opposite flat walls into which the slabbed cylinder 34 of the lock fits. The rotatable barrel of the lock and the key-operated mechanism is the same as that heretofore described. In this construction the cylinder is provided at its outer end with an integral inwardly converging conoidal head 35 and the barrel of the cylinder has welded or otherwise fixedly secured thereto an eccentric disk 36. The end portion of the body 33 is provided with a bore 37 which is eccentric to the axis of the rotatable barrel of the lock to receive the end of one leg of a U-shaped hasp. The same end of the body 33 is also provided with a bore 38 diametrically opposite to the bore 37 to receive the other longer leg 39 of the U-shaped hasp which has at its end a head 40 which slidably fits the bore 38. A cap 41 complementary to and registering with the body 33 approximately on the section line 7-7 Fig. 5 is provided with a bore 42 which registers with the bore 38 and extends upwardly approximately to the upper surface of the cap. The cap has also a bore 43 through which the other leg 44 of the hasp may be inserted into the bore 37. The cap is provided with a lateral recess 45 to receive the eccentric disk 36 upon the end of the barrel. The cap thus constructed may be welded or otherwise fixedly secured to the body of the lock upon assemblage of the lock in such manner as to prevent its detachment therefrom. A spring 46, which is interposed between the head 40 of the hasp and the end wall of the bore 42, normally tends to force the leg 44 of the hasp into the bore 43 and the countersink 37. The hasp is provided with a slot or notch 47 adapted to be engaged by the eccentric disk 36 upon rotation of the disk to locking position illustrated in Fig. 6.

The operation of the lock is similar to that heretofore described, and is such that when the disk 36 is rotated to locking position illustrated in Fig. 6 the key can be removed from the lock, but when the barrel of the lock is rotated by the key in a direction to disengage the eccentric 36 from the notch 47 the key cannot be withdrawn from the lock. By reason of this construction a padlock is provided in which the hasp normally tends to return to locking position to be engaged by the eccentric 36.

When it is desired to lock two relatively movable members together the hasp is rotated about the axis of the leg 39 so that the leg 44 extends beyond the side of the body whereupon it can be inserted through the staple of a pair of complementary locking members, then swung into alignment with the bore 43, whereupon the spring 46 will force the leg 44 into locking position so that the eccentric disk 36 may be moved into engagement with the notch 47 on the leg 44 by rotation of the key in a proper direction. When thus locked the key can be withdrawn.

When it is desired to remove the padlock the key may be rotated in the opposite direction to remove the eccentric disk 36 from engagement with the notch 47 and by pulling upon the body of the lock it can be rotated about the axis of the leg 39 in such manner as to permit the hasp to be withdrawn from the staple or other member to which the lock is secured. Upon rotation of the hasp about the axis of its leg 39 the leg 44 will be brought into registry with the bore 43 in the head and the hasp returned to locking position so that the key can be rotated in a direction to permit its removal from the lock. If, however, the hasp is not rotated into alignment with the bore 43 in the head the key can still be removed by rotating the disk 36 to locking position, in which case the leg 44 of the hasp cannot be inserted into locking position.

In order to prevent the entry of water, dust, etc. into the keyhole of the lock illustrated in Figs. 1-4 inclusive a suitable cap in the form of a disk 48 is provided with inwardly extending spring tangs 49 which may be snapped over the conical head of the barrel.

Locks of this character are adapted to be provided with numerous combinations of tumbler pins and keys respectively therefor so that a multitude of different locks with a suitable key for each may be provided.

By reason of the present invention a lock of simple construction may be made at a relatively low cost which will be certain of operation indefinitely. As a matter of fact a door lock construction embodying the invention can be pro-

duced in which the complementary pins or tumblers of the lock are arranged vertically and the usual spring for forcing the pins in the body of the lock actuated by gravity thereby enabling the omission of the springs 23 thus providing an entirely springless lock.

It will be understood that the particular embodiments of the invention shown and described herein are of an illustrative character and not restrictive of the meaning and scope of the claim.

- Having thus described the invention, what is claimed as new, and desired to be secured by Letters Patent, is:
- 15 A sliding door lock for releasably securing together two relatively slidable members when in edge to edge abutting position comprising an angle plate having a flange secured to the edge of one of said members and another flange extending outwardly therefrom provided with a slot leading to a circular recess of greater diameter than the width of said slot, a lock body embedded in and fixedly secured to the other door member having a key-operable cylindrical tumbler controlled barrel provided with oppositely disposed narrow slots parallel to the key-hole slidably to fit within the slot in said angle plate, when said members are moved to abutting position, with a cylindrical barrel registering with said circular recess and operable upon rotation of the key to position the slots in the barrel transversely of the slot in the angle plate thereby to prevent withdrawal of the barrel through said slot, and means for preventing withdrawal of the key when the barrel is rotated to lock-releasing position.
